UNITED STATES PATENT OFFICE.

GEORGE HUGH HARRY JONES, OF CAMDEN, NEW JERSEY, ASSIGNOR TO GENERAL CHEMICAL COMPANY, OF NEW YORK, N. Y., A CORPORATION OF NEW YORK.

CARBOY PACKAGE.

Application filed May 22, 1924. Serial No. 715,007.

My invention relates to packages for containing and protecting carboys during transportation and more particularly to that type of such packages which include clamping strips and wedging means and of which an example is shown in United States Patent No. 1,000,449 to Karl F. Stahl. The object of the invention is to provide a novel and improved construction in which special provision is made for preventing unintentional displacement of the wedging means relatively to the clamping strips. Other more specific objects will appear from the description hereinafter and the features of novelty will be pointed out in the claims.

In the accompanying drawings, which illustrate an example of the invention without defining its limits, Fig. 1 is a sectional elevation of a carboy package embodying the invention taken on the line 1-1 of Fig. 2; Fig. 2 is a plan view with the cover removed; Fig. 3 is a perspective view of the wedging means and Fig. 4 is a similar view of a clamping strip. The package in its illustrated form comprises the usual outer crate or box 10 having the customary bottom 11 upon which horizontal supporting strips 12 may be mounted in crossed relation and extending diagonally across said crate 10; in the preferred arrangement the strips 12 are spaced from the bottom 11 by spacing members 13 of suitable form. These strips 12 are generally of soft wood and constitute a support on which the carboy 14 rests when in position in the package.

For the purpose to be more fully described hereinafter triangular corner pieces 15 are fitted in the corners of the crate 10 so as to extend lengthwise thereof. Upright clamping strips 16, preferably also of soft wood, are located adjacent to each corner of the crate 10 and have their lower ends suitably secured to or braced against blocks 17 which are secured in each corner of said crate for instance just above the strips 12 as shown in Fig. 1. The arrangement is such that the clamping strips 16 extend lengthwise of the corner pieces 15 of the crate 10 as illustrated in Fig. 1; said clamping strips 16 being somewhat flexible and of such length as to extend above the body of the carboy 14. For the purpose of forcing the strips 16 into clamping engagement with the carboy 14 wedges

18 are inserted between the upper ends of the strips 16 and the corner pieces 15 and thereby curve the upper ends of said strips 16 inwardly as shown in Fig. 1. In order to prevent the wedges 18 from being unintentionally displaced relatively to the strips 16 and from dropping down between said strips and the corner pieces 15 improved construction in which special provision is made for preventing unintentional displacement of the wedging means relatively to the clamping strips. Other more specific objects will appear from the description hereinafter and the features of novelty will be pointed out in the claims.

In the accompanying drawings, which illustrate an example of the invention without defining its limits, Fig. 1 is a sectional elevation of a carboy package embodying the invention taken on the line 1-1 of Fig. 2; Fig. 2 is a plan view with the cover removed; Fig. 3 is a perspective view of the wedging means and Fig. 4 is a similar view of a clamping strip. The package in its illustrated form comprises the usual outer crate or box 10 having the customary bottom 11 upon which horizontal supporting strips 12 may be mounted in crossed relation and extending diagonally across said crate 10; in the preferred arrangement the strips 12 are spaced from the bottom 11 by spacing members 13 of suitable form. These strips 12 are generally of soft wood and constitute a support on which the carboy 14 rests when in position in the package.

For the purpose to be more fully described hereinafter triangular corner pieces 15 are fitted in the corners of the crate 10 so as to extend lengthwise thereof. Upright clamping strips 16, preferably also of soft wood, are located adjacent to each corner of the crate 10 and have their lower ends suitably secured to or braced against blocks 17 which are secured in each corner of said crate for instance just above the strips 12 as shown in Fig. 1. The arrangement is such that the clamping strips 16 extend lengthwise of the corner pieces 15 of the crate 10 as illustrated in Fig. 1; said clamping strips 16 being somewhat flexible and of such length as to extend above the body of the carboy 14. For the purpose of forcing the strips 16 into clamping engagement with the carboy 14 wedges

18 are inserted between the upper ends of the strips 16 and the corner pieces 15 and thereby curve the upper ends of said strips 16 inwardly as shown in Fig. 1. In order to prevent the wedges 18 from being unintentionally displaced relatively to the strips 16 and from dropping down between said strips and the corner pieces 15 improved construction in which special provision is made for preventing unintentional displacement of the wedging means relatively to the clamping strips. Other more specific objects will appear from the description hereinafter and the features of novelty will be pointed out in the claims.

In the accompanying drawings, which illustrate an example of the invention without defining its limits, Fig. 1 is a sectional elevation of a carboy package embodying the invention taken on the line 1-1 of Fig. 2; Fig. 2 is a plan view with the cover removed; Fig. 3 is a perspective view of the wedging means and Fig. 4 is a similar view of a clamping strip. The package in its illustrated form comprises the usual outer crate or box 10 having the customary bottom 11 upon which horizontal supporting strips 12 may be mounted in crossed relation and extending diagonally across said crate 10; in the preferred arrangement the strips 12 are spaced from the bottom 11 by spacing members 13 of suitable form. These strips 12 are generally of soft wood and constitute a support on which the carboy 14 rests when in position in the package.

For the purpose to be more fully described hereinafter triangular corner pieces 15 are fitted in the corners of the crate 10 so as to extend lengthwise thereof. Upright clamping strips 16, preferably also of soft wood, are located adjacent to each corner of the crate 10 and have their lower ends suitably secured to or braced against blocks 17 which are secured in each corner of said crate for instance just above the strips 12 as shown in Fig. 1. The arrangement is such that the clamping strips 16 extend lengthwise of the corner pieces 15 of the crate 10 as illustrated in Fig. 1; said clamping strips 16 being somewhat flexible and of such length as to extend above the body of the carboy 14. For the purpose of forcing the strips 16 into clamping engagement with the carboy 14 wedges

18 are inserted between the upper ends of the strips 16 and the corner pieces 15 and thereby curve the upper ends of said strips 16 inwardly as shown in Fig. 1. In order to prevent the wedges 18 from being unintentionally displaced relatively to the strips 16 and from dropping down between said strips and the corner pieces 15 improved construction in which special provision is made for preventing unintentional displacement of the wedging means relatively to the clamping strips. Other more specific objects will appear from the description hereinafter and the features of novelty will be pointed out in the claims.

21, at points above the body of the carboy so that the possibility of said wedges becoming interposed between the strips and the corner pieces in registry with the body is obviated; the wedges 18 therefore can never unintentionally reach a position in which they may transmit shocks to the carboy in such a way as to injure or break the same. If the shoulders 21 are sloping in form, as 10 is preferred, the co-operation of the ribs 19 therewith will firmly hold the wedge against rising and thereby springing out of place. The ribs 19, by engagement with the opposite edges of the strips 16 serve to prevent unintentional displacement of the wedges relatively to said strips in directions transverse to the length thereof.

The invention is simple in construction and efficient in operation and effectively overcomes an objection heretofore inherent in carboy packages of the indicated type.

Various changes in the specific form shown and described may be made within the scope of the claims without departing 25 from the spirit of my invention.

I claim:

1. In a carboy package, the combination of a receptacle, a plurality of upright strips arranged within said receptacle and constructed and arranged to extend lengthwise of a carboy, a plurality of wedges each movably located between a strip and a contiguous portion of the receptacle for independently forcing the upper ends of said strips inwardly whereby the carboy is clamped between the strips, and cooperating means on said strips and wedges whereby unintentional displacement of the latter relatively to said strips and container is arrested.
2. In a carboy package, the combination of a receptacle, a plurality of flexible upright strips arranged within said receptacle and constructed and arranged to extend lengthwise of the carboy and upwardly beyond the body thereof, a plurality of wedges each located between the upper end of a strip and a contiguous portion of the receptacle and movable lengthwise of said strip for independently forcing the upper ends of said strips inwardly whereby the carboy is clamped between the strips, and cooperating means on said strips and wedges whereby the extent of the downward movement of the wedges relatively to said strips is predetermined and further relative downward movement is arrested at predetermined points above the body of the carboy.
3. In a carboy package, the combination of a receptacle, a plurality of flexible upright strips located within said receptacle

and constructed and arranged to extend lengthwise of a carboy, a plurality of wedges each located between the upper end of the strip and a contiguous portion of the receptacle and movable lengthwise of said strip for independently forcing the upper ends of said strips inwardly whereby the carboy is clamped between the strips, and means on said wedges whereby unintentional displacement thereof relatively to said strips in transverse directions is prevented without interference with the lengthwise movement of said wedges.

4. In a carboy package, the combination of a receptacle, a plurality of upright strips located within the same and constructed and arranged to extend lengthwise of a carboy, said strips being of reduced width at their upper end portions, shoulders on said strips at the junction of the reduced portions with the wider portions thereof, a plurality of wedges for independently forcing the upper ends of the strips inwardly whereby the carboy is clamped between said strips and means on said wedges co-operating with said shoulders to arrest an unintentional dropping of the wedges lengthwise of the strips.

5. In a carboy package, the combination of a receptacle, a plurality of upright strips located within the same and constructed and arranged to extend lengthwise of a carboy, said strips being of reduced width at their upper end portions and flaring outwardly in downward directions to form sloping shoulders, a plurality of wedges for independently forcing the upper ends of said strips inwardly whereby said carboy is clamped between the strips and ribs extending lengthwise of the wedges in pairs and fitted upon the reduced end portions of said strips, said ribs being arranged to co-operate with said sloping shoulders to arrest unintentional downward movements of said wedges relatively to said strips.

6. In a carboy package, the combination of a receptacle, a plurality of upright strips located within the same and constructed and arranged to extend lengthwise of a carboy, a plurality of wedges each located between the upper end of a strip and a contiguous portion of the receptacle for independently forcing the upper ends inwardly to clamp the carboy in said receptacle, and ribs extending lengthwise of said wedges in pairs and overlapping opposite edge surfaces of said strips to prevent lateral displacement of each wedge relatively to its strip.

In testimony whereof I have hereunto set my hand.

HUGH HARRY JONES.
